POULTRY SHEARS OR SIMILAR ARTICLE

Gastone Centa, 46 Via Roma, Maniago, Udine, Italy

Filed Feb. 3, 1966, Ser. No. 899

Claims priority, application Italy Oct. 16, 1965

Term of patent 7 years

(Cl. D22—5)

FIG.6

FIG.7

FIG.8

FIG. 1 is a view in perspective of poultry shears or similar article in closed position showing my new design;

FIG. 2 is a view in elevation of one side thereof;

FIG. 3 is a view in elevation of the opposite side thereof;

FIG. 4 is a view in elevation of one edge thereof;

FIG. 5 is a view in elevation of the opposite edge thereof;

FIG. 6 is a cross-sectional view on an enlarged scale taken on line 6—6 of FIG. 2;

FIG. 7 is a view in elevation corresponding to FIG. 2, but with the shears in open position, and

FIG. 8 is a view in elevation corresponding to FIG. 3, but with the shears in open position.

I claim:

The ornamental design for a poultry shears or similar article, as shown.
